UNITED STATES PATENT OFFICE.

WALTER B. BROWN, OF NEWARK, NEW JERSEY, ASSIGNOR TO THE BIGELOW CARPET COMPANY, OF MASSACHUSETTS.

DESIGN FOR CARPET.

SPECIFICATION forming part of Design No. 27,410, dated July 20, 1897.

Application filed June 7, 1897. Serial No. 639,766. Term of patent 3¹ years.

To all whom it may concern:

Be it known that I, WALTER B. BROWN, a subject of the Queen of Great Britain, and a resident of Newark, in the county of Essex and State of New Jersey, have invented a new and original Design for Carpets and Borders, of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention.

The body A is characterized by large figures substantially circular in form, which are surrounded by smaller figures having substantially an oval configuration. In the body A, as shown in the drawing, one half of a large figure is shown at a, and a complementary half of another such large figure is shown at a'.

The border B is characterized by a panel of urn-like figures alternating with figures of substantially oval configuration; also by an outer panel of scrollwork.

What I claim as new, and desire to secure by Letters Patent, is—

1. In a design for a carpet, the body A, substantially as shown. 30
2. In a design for a carpet, the border B, substantially as shown.
3. The design for a carpet comprising the body A and the border B, substantially as shown. 35

In testimony whereof I have signed my name to this specification in the presence of two subscribing witnesses.

WALTER B. BROWN.
